WILLIAM F. WASHBURN, OF NEWARK, NEW JERSEY.

CARBURETER.

1,123,048.

Specification of Letters Patent. Patented Dec. 29, 1914.

Application filed November 10, 1911. Serial No. 339,530.

To all whom it may concern:

Be it known that I, WILLIAM F. WASHBURN, a citizen of the United States, and a resident of Newark, in the county of Essex and State of New Jersey, have invented a new and Improved Carbureter, of which the following is a full, clear, and exact description.

My invention relates to carbureters of the kind employed upon internal combustion engines, explosion motors, and the like, for the purpose of preparing explosive mixtures of a hydro-carbon and air.

More particularly stated, my invention comprehends a carbureter having mechanical features by aid whereof the proportion of air and a hydro-carbon is regulated with great nicety at the will of the operator, and under certain conditions is rendered automatic in the sense that the proportion of air and hydro-carbon is changed, within certain limits, to suit variations in the speed of the machine and in the capacity of the carbureter as the latter is taxed to varying degrees due to the vicissitudes of speed and under changes of load.

My improved carbureter makes special provision for increasing the proportion of air supplied per unit of explosive mixture as the speed of the engine or its equivalent is increased, and also for enabling the operator to adjust the refinement of the proportion to suit varying needs based upon variations of speed and load.

Reference is to be had to the accompanying drawing forming a part of this specification, in which like characters of reference indicate corresponding parts in all the views, and in which—

Figure 1 is a central vertical section through the carbureter complete; Fig. 2 is a top plan view of the carbureter; Fig. 3 is a bottom plan view of the same; Fig. 4 is a section on the line 4—4 of Fig. 1, looking in the direction of the arrow; Fig. 5 is a section on the line 5—5 of Fig. 1, looking in the direction of the arrow; and Fig. 6 is a detail view of the valve shown in section in Fig. 1.

A mixing chamber is shown at 6, and has the form of a barrel, the inner diameter of which is slightly reduced at the upper end. Integral with the mixing chamber 6 and flush with the upper end thereof are extensions 7, provided with threaded holes 8, the

purpose of which is to accommodate bolts, 55 and thus facilitate the mounting of the carbureter upon an engine or the like. A throttle 9, having the form of a butterfly valve, is located within the mixing chamber, and may be turned to different angles for 60 the purpose of closing the mixing chamber to any desired extent. This throttle is mounted upon a pair of stub shafts 10, 12, the stub shaft 10 turning in a bearing 11, and the stub shaft 12 in a bearing 13. An 65 arm 14 is mounted rigidly upon the stub shaft 12, and is used for turning the throttle 9.

An annular plate 15 encircles the mixing chamber 6, and is provided with bearings 70 15^a having generally the form of ears. These ears are provided with threaded holes 16, and fitting into the latter are threaded tubular stems 17. These stems carry nuts 18, each having generally a cup-like form, 75 as will be understood from Fig. 1, and each is provided externally with a knurled edge to facilitate its rotation by hand. Smooth bolts 19 extend through the tubular stems 17, and are provided at their upper ends 80 with annular stops 20, through which extend pins 21 for holding them rigidly in position. Spiral springs 22 engage the annular stops 20, and also engage the nuts 18 extending into the latter, as will be understood from Fig. 1.

A concentric valve 23 of considerable size and having a general annular form is provided with openings located close to its outer edge and through which the bolts 19 extend, 85 the bolts, at their lower ends, being provided with heads 24 integral therewith, which engage the under side of the valve 23.

The annular plate 15 is provided with a valve seat 25 extending downwardly from 95 its outer edge, and mating the outer edge of the valve 23. The inner edge of the plate 15 is provided with a thread 26, which mates a similar thread upon the outer surface of the mixing chamber. By turning the plate 15 100 relatively to the mixing chamber, the plate may be raised or lowered within certain limits, as will be understood from Fig. 1. The plate 15 is further provided with an annular shoulder 27, and lodging against 105 this shoulder is a substantially bowl-shaped member 28, the upper edge of which is provided with a thread 29 mating a similar

- thread carried by the plate 15 at a point adjacent to the shoulder 27. This bowl-shaped member 28 and parts co-acting with it together constitute an adjustable air-chamber. 5 The lower end of the bowl-shaped member 28 is provided with a flange 30, which is threaded externally. A yoke 32, having a ring 31 formed integral therewith, the ring being threaded internally, is fitted upon the 10 threaded flange 30. This yoke is further provided with a sleeve 33, which is smooth internally.

A sleeve 34, which is threaded externally, extends through the smooth sleeve 33 and is 15 internally connected with a yoke 35. This yoke fits into the lower end of the flange 30 and is provided with a seat 36, which may be provided with a number of air-holes 57 extending therethrough. Through the 20 threaded sleeve 34, and co-axial with the same, is another sleeve 38, which is threaded externally and fits loosely into the sleeves 34. The lower end of the sleeve 38 is enlarged and provided internally with a 25 threaded portion 39, to facilitate connection between the sleeve and a supply line. A nut 40 is threaded internally and fitted upon the sleeve 38. Two other nuts 41, 42 are threaded internally and fitted upon the sleeve 34. 30 A nut 43 is threaded internally and fitted upon the sleeve 38 and is adapted to fit neatly against the bottom of the yoke 35. The sleeve 38 is provided with a smooth portion 44 of reduced diameter, and is further 35 provided with a cylindrical passage 45. A bushing 46 is mounted within this passage, and is used for restricting the flow of hydro-carbon. A tapered needle 47 is positioned within the passage 45, and serves the 40 purposes of a valve in regulating the flow of hydro-carbon.

Mounted upon the needle 47 is a valve member 48, which normally rests upon the upper end of the sleeve 38 and serves to close 45 the said upper end, which is fashioned into a valve seat. A neck 49 integral with the needle 47 extends upwardly from the valve member 48, and mounted adjacent the top of the neck is a button or plate 50 providing 50 a large surficial area for the actuation of the valve 48 in a manner to be hereinafter more fully set forth; the neck is of reduced diameter adjacent the button, a shoulder 49' resulting thereby. Whenever this 55 button is raised by a vacuum in the mixing chamber and by the atmospheric pressure, it carries with it the neck 49 and needle 47, thus raising the valve 48 just mentioned. A spring 51 encircles the reduced portion of the neck 49 and engages the end 53 and the shoulder 49' to normally seat the valve 48. A tubular sleeve 52 is provided with a constricted end portion 53, and the spring 51 fits into the latter. The sleeve 52 is provided with openings 54 disposed adjacent to

its upper end, and at its lower end is provided externally with a threaded portion 55. A nut 56 is threaded and fitted upon this threaded portion. A spiral spring 57^a engages the nut 56, and also engages the under side of the seat 36. A lifting plate 58 rests upon the seat 36, and is provided with a bearing sleeve 59 encircling the sleeve 52. This lifting plate 58 is provided with posts 60, secured rigidly upon it and extending directly upward from it and in proximity to the button 50.

By adjusting the nuts 40 and 43, the sleeve 38 may be raised or lowered, thereby adjusting the spring 51 and regulating the pressure of the cut-off valve 48 upon its seat, and also restricting the flow of hydro-carbon at slow speeds. The lifting plate 58 is adapted to be raised by atmospheric pressure, and increases the sensitiveness of the spring 51. 75

The operator, by turning the nuts 41, 42, can raise the sleeve 34 relatively to the yoke 32, and in doing this, he can also adjust the position of the seat of the valve 48 relatively to the air chamber 28. The effect of this is to find the best position for the air to strike the vapor under various conditions. Under some vicissitudes of work of the carbureter, this adjustment is desirable; that is to say, this carbureter is, by experience, 90 found to work better under some conditions when the openings 54 are raised fairly well up into the lower end of the mixing chamber, so that the blast of air going through the throttle when the engine is sucking in air has more of an aspirating effect upon the openings 54 than is the case when the sleeve 52 is in its lowermost position. By adjusting the nut 56, the flow of hydro-carbon 95 may be regulated in order to meet the various conditions to which the motor may be subjected at intermediate and high speeds. 100

I have found from experience that the valve member 48 can be rendered exceedingly sensitive when this effect is desired, 110 by peculiar adjustments of either of the nuts 18. Suppose, for instance, that the nut 18 at the left of Fig. 1 be so adjusted that the spring 22 is compressed to a considerable degree and that the nut 18 be turned so as to compress the spring 22 to a lesser degree. This enables the valve 23 to be opened a little easier upon its right side than upon its left side; that is to say, while the valve 23 is drawn straight downward 115 and maintains its approximate horizontal position, yet there is a slight—even imperceptible—tilting of the valve in the sense that portions of it disposed at the right of Fig. 1 are moved away from the valve seat 120 25 and thus enable a little air to pass the valve 23. I find that by an adjustment of the kind just described the air in displacing the valve 23 and entering the mixing chamber represented by the air chamber 28 is in- 125 130

ducted with a degree of positiveness not obtained in constructions of usual kind. I suppose this effect is due to the fact that the valve member 23, by its tilting slightly at 5 one of its edges, enables the air to serve somewhat after the manner of an entering wedge and thus prevent the valve from sticking upon its seat.

The operation of my device is as follows:—The parts being adjusted as above described, the engine being started by opening the throttle 9, a partial vacuum is periodically produced within the mixing chamber lifting the button 50 and the plate 58, the latter being also raised by the atmospheric pressure. This movement of the button and plate also carries the posts 60 and the needle 47 upwardly, thereby allowing the hydrocarbon to pass through the valve 48 and through the openings 54 into the mixing chamber 6. The hydrocarbon is atomized in the mixing chamber by the incoming air which enters through the holes 57 in the seat 36, the gradual opening of 15 the throttle increasing the suction, thereby raising the needle 47 until the shoulder 49 thereon comes into contact with the restricted end 53 of the sleeve 52; after such contact has occurred the needle 47 on further 20 movement raises the sleeve 52 and increases the tension on the spring 57, such further movement after contact occurring at intermediate and high speeds. The travel of the parts just described occurs in unison with 25 the air valve 23, which covers and uncovers the openings leading to the mixing chamber, the result being that the plate 58 is held suspended and away from the seat 36 by atmospheric pressure, the object of this plate being to hold the valve 48 off the valve seat, thereby steadyng the engine at low speeds. By reason of the valve 23, plate 58 and valve 48 being held closed, as described, such valves act as automatic check valves 30 to prevent back-firing through the manifold and carbureter during the intake stroke of the engine, while said valve and plate are also held closed on the compression or operative strokes of the engine. If, now, the 35 speed be increased without any change in the adjustment of the various parts, or if the engine be stopped and the valve member 23 be adjusted to a finer degree of sensitiveness as above described, this valve member is drawn away from its seat and the air enters freely into the mixing chamber. The supply of air through the holes 57 being already at a maximum, as above described, the enormous increase of air due to the 40 placement of the valve member 23 renders the total supply of air adequate to supply the increased demand.

It will be noted from the description given that the valve 48 is movable independently of movement of the plate 58 and

may also be moved through movement of such plate by reason of the engagement of the posts 60 with the button 50. Movement of the plate 58 admits air to the mixing chamber and movement of the valve 48 admits a hydro-carbon thereto, increase in the movement of the plate providing for an increase of air, which, in turn, provides for an increase in hydro-carbon, due to the added travel of the valve 48 through movement of the plate; the valve 48 then partakes of successive movements, the hydro-carbon being admissible without the entrance of air through the holes 57 and being also admissible along with the admission of 80 air through these holes.

From the foregoing description it will be noted that this carbureter has an exceptionally wide range of adjustments, and, moreover, that the various adjustments admit of 85 an exceptionally large degree of refinement. One result of this is that the carbureter has a degree of positiveness in action and also has an exceptional degree of adaptability in adjusting itself to various degrees of operation.

Having thus described my invention, what I claim as new and desire to secure by Letters Patent is:—

1. A carbureter comprising a mixing 95 chamber, openings therein for admitting air thereto, a movable member adapted to cover and uncover the said openings, a suction stroke of the engine moving the said member to uncover the openings, a valve 100 for admitting a hydrocarbon to the said chamber, a movable member, adapted to open the said valve, a suction stroke of the engine moving the member to open the valve, means for maintaining the said movable members in such position that the openings are covered and the valve is closed, whereby back-firing through the carbureter is prevented, during the intake stroke of the engine.

2. A carbureter, comprising a mixing chamber adapted to supply an explosive mixture to an engine, there being openings in the chamber for admitting air thereto, means for covering the openings, a valve 115 automatically operative for admitting a hydrocarbon to the chamber on the intake stroke, means for keeping the valve closed, suction of the engine automatically moving said first named means to uncover the openings, there being other openings communicating with said chamber interiorly and means normally covering said openings last-named and controlled by the suction of the engine for opening said valve during the 125 suction of the engine.

3. A carbureter comprising a mixing chamber having provision for admitting air thereto, a valve controlled by the suction of the engine for admitting a hydro- 130

carbon, and other means also actuated by the suction of the engine for further opening the said valve.

4. A carbureter comprising a mixing chamber having provision for admitting air thereto, a valve for admitting a hydrocarbon, the said valve comprising a passageway, a spring-pressed member normally closing the passageway, the said member 10 moving to open the passageway during a suction stroke, and additional means for further moving the said member during such suction stroke.

5. A carbureter, comprising a mixing chamber having openings therein for admitting air thereto, a spring-actuated valve for admitting a hydrocarbon thereto on the intake stroke, said valve having a plate-like upper end whereby its opening will be assisted by atmospheric pressure and upon a vacuum being created in the mixing chamber, a plurality of independently movable devices for covering and uncovering said openings and for opening and closing the 20 valve and adjustable spring-actuated means for maintaining said devices in one position whereby the suction of the engine will move the same to the second position.

6. A carbureter comprising a mixing chamber having provision for admitting air thereto, means for admitting a hydrocarbon to the mixing chamber, primary suction controlled means for opening said hydrocarbon admitting means, and a secondary suction controlled means for further opening said hydrocarbon admitting means.

7. A carbureter comprising a mixing chamber having provision for admitting air thereto, a valve for admitting a hydrocarbon, primary suction controlled means for opening the valve, the valve being adapted for successive movements whereby the amount of hydrocarbon admitted is increased, means for determining the initial movement of the valve, and other means controlled by the suction of the engine for imparting further movement thereto.

8. A carbureter comprising a mixing chamber having provision for admitting air thereto, a valve for admitting a hydrocarbon, the valve being adapted to partake of a plurality of movements, suction of the engine opening the valve, and a movable member also controlled by suction of the engine for imparting further movement to the valve, whereby the supply of hydrocarbon during such further movement is increased.

9. A carbureter comprising a mixing chamber having a valve for controlling the admission of air, and a second valve for controlling the admission of hydrocarbon, the air control valve comprising a substantially annular member having independently adjustable means at diametrically op-

posite points to regulate the opening of the valve.

10. A carbureter comprising a mixing chamber, a valve for controlling the admission of air thereto, and a suction valve for controlling the admission of a hydrocarbon thereto, means for maintaining the air valve normally closed, the said air valve comprising a substantially annular member having a plurality of independently adjustable means, whereby the pressures on the valve due to the said means may be varied.

11. In a carbureter, the combination of a member for discharging a hydrocarbon, valve mechanism for opening and closing the said member in order to control the said discharge of hydrocarbon therefrom, the said valve mechanism including a button, a lifting plate, extensions on the lifting plate, the said extensions being adapted to co-act with the button to raise the needle from the valve seat, together with a number of air holes to admit air into contact with the hydrocarbon thus discharged, the said lifting plate and mechanism connected with the lifting plate actuating the said valve mechanism.

12. In a carbureter, the combination of a mixing chamber, means for admitting hydrocarbon vapor thereinto, a valve member for admitting air in large quantities into said hydrocarbon chamber, and means controllable at will for adjusting a portion of said valve member to greater sensitiveness than another portion thereof in order to facilitate the movement of said valve member under atmospheric pressure.

13. In a carbureter, the combination of a chamber provided with holes for admitting air, a sleeve for discharging hydrocarbon thereinto, a lifting plate for opening and closing the said sleeve in order to control the discharge of the said hydrocarbon into the mixing chamber, and mechanism connected with said sleeve for actuating the said lifting plate.

14. In a carbureter, the combination of a mixing chamber, a throttle extending thereto, means for discharging a hydrocarbon substance into said mixing chamber, a valve seat encircling said throttle, an annular valve mating said seat and also encircling said throttle, a plurality of separate members engaging said annular valve for normally holding the same upon said seat, and means controllable at will for adjusting one of said members to a greater degree of sensitiveness than another.

15. A carbureter comprising a mixing chamber, a throttle extending thereto, a valve seat disposed within said mixing chamber, a valve member detachably engaging said seat, a plurality of bolts extending through said valve member, springs connecting said bolts, and means for controlling at will the

tension of said springs in order to enable one of said bolts to press harder than another upon said valve member.

16. In a carbureter, the combination of a mixing chamber, a valve seat mounted therein, a throttle housing extending into said mixing chamber, means for adjusting said valve seat relatively to said throttle housing, a valve member mounted upon said valve seat and adapted, when displaced therefrom,

to admit air into said mixing chamber, and means for admitting a hydrocarbon vapor into said mixing chamber.

In testimony whereof I have signed my name to this specification in the presence of 15 two subscribing witnesses.
